UNITED STATES PATENT OFFICE

91,525

DESIGN FOR A STORAGE BATTERY CASE

Frank T. Kalas, Philadelphia, Pa.

Application May 29, 1933. Serial No. 48,243

Term of patent 14 years

To all whom it may concern:

Be it known that I, FRANK T. KALAS, a citizen of the United States, residing at Philadelphia, in the county of Philadelphia and State of Pennsylvania, have invented a new, original, and ornamental Design for a Storage Battery Case, of which the following is a specification, reference being had to the accompanying drawing, forming part thereof.

Fig. 1 is a view in elevation of a storage battery case showing the novel design applied thereto; and

Fig. 2 is a perspective view on a reduced scale, showing surface ornamentation intended to represent the same ornamentation as shown in Fig. 1, and showing an indented oval which serves as the conventional place for the location of the name.

I claim:

The ornamental design for a storage battery case, as shown and described.

FRANK T. KALAS.
